UNITED STATES PATENT OFFICE.

STEPHEN L. MERSHON, OF LLANERCH, PENNSYLVANIA.

DEVICE FOR AUTOMATICALLY CONTROLLING PILOT LIGHTS OF HEAVY-OIL BURNERS
FOR FURNACES, BOILERS, AND THE LIKE.

Application filed January 17, 1923. Serial No. 613,119.

My invention relates to burners in which heavy atomized oils are employed as fuel, and which are used for heating boilers and hot-water heaters, for manufacturing and domestic purposes, and particularly to the provision of means whereby such heavy fuels may be ignited automatically, with certainty and facility when the burner and the fuel are both cold.

In such burners it has been common to locate a continuously burning pilot light within the pot or burner into which the atomized fuel is projected by air pressure and to depend upon that pilot light to ignite the fuel. It has also been attempted to provide an automatic arrangement whereby, when the fuel is about to be projected into a cold burner, the flow of illuminating gas through the pilot light is momentarily increased, to make certain the ignition of the cold atomized fuel. In such devices, however, the means for automatically closing the circuit to the motor for rotating the fan by means of which the heavy fuel is atomized and projected into the furnace, is depended upon to give a momentary increase in the flow of illuminating gas at the pilot light. The same device, which increases the flow of gas also cuts down the flow of gas, so that at or about the time the fan is in full operation, the flow of gas through the pilot light is reduced back to the normal small pilot light flow.

This momentary increase in the size of the pilot light flame is insufficient to be absolutely depended upon. Unless the device for closing the current to the motor operates very slowly and continues its operation for some time after the motor has been energized and the fan set into motion thereby, the momentary flare of the pilot light will have been completed, the small pilot light flame will be all that there is to start the ignition of the fuel, and as above indicated, that will often fail to ignite the incoming cold fuel.

It is the object of my invention to provide a device of the character above described wherein the automatic mechanism for closing the circuit to the motor, in coming to a position where the circuit is closed to start the motor, will be operative to open the valve controlling the pilot light to substantially greatly increase the flow of the illuminating gas to the pilot light, and will maintain that increased flow and the large pilot light flame, resulting

thereon, until the furnace or heater shall become heated to a predetermined extent by the ignition or combustion of the atomized fuel. The purpose of my invention is therefore to provide means substantially independent of but cooperating with the means for increasing the flow of gas through the pilot light, for diminishing that relative large flow after the furnace has attained a predetermined temperature.

Other objects of my invention will appear in the specification and claim below.

Referring to the drawings forming a part of this specification, I have illustrated one type of heavy liquid fuel burner for domestic purposes, suitable for heating domestic boilers, or domestic hot-water heaters, and in this drawing the parts of the burner and their relation with respect to the furnace or boiler are more or less diagrammatically indicated.

Thus, the electric motor 1 is directly connected by a shaft 2 to an oil pump 3 and to a fan (not shown) in a suitable fan casing 4 which when rotated forces air through the nozzle 5 into the pot or burner 6 where it is consumed. Oil may be supplied through a pipe 7 to the oil pump 3 whence it is forced through the pipe 8 into the fan casing and into the nozzle 5 where it is atomized by the air blast. A return drip pipe 9 provides a means for conducting excess oil which might accumulate in the burner without being ignited, back into the oil supply reservoir.

A thermostat 10 may be located in any room to be heated by the furnace or boiler. When, for instance, the finger 11 thereof swings over to the contact point 12 by reason of the lowering of the temperature of the room, then a circuit is closed through the wire 13, the operating mechanism 14, the wire 15, battery 16 and finger 11, to release a trip in the starting mechanism 14, and the crank 18 will automatically revolve through one-half a revolution. When the arm 18 shall have completed said half of a revolution, it will engage the contact point 19, to close the circuit to the motor 1 through the wires 20 and 21 which may be connected to any suitable source of electric energy, and will then stop in that position. When the temperature of the room thereafter rises to a predetermined point, to which the thermostat 10 may be set, the finger 11 will have swung to the opposite contact point 22 to

close a circuit through the wire 23, operating mechanism 14, wire 15, battery 16 and finger 11 to again release the escapement or trip in the operating mechanism 14, whereupon the crank or arm 18 will now swing through the second half of its revolution back to the position shown in Fig. 1, breaking the circuit to the motor, and consequently cutting off the supply of fuel to the burner 6. As above indicated, the operating mechanism and the thermostat are merely diagrammatically shown, and they may be of any well-known or approved design.

Within the pot or burner 6 is a pilot light burner 24, which, through suitable piping 25, is connected to any suitable source of illuminating gas. The supply of gas to the pilot burner 24 is controlled by a valve 26 provided with a lever 27. When the lever 27 is in the position shown in the drawing, a minimum amount of gas is allowed to flow through the pipe 25 through the burner 24, that is to say, an amount of gas merely sufficient to maintain a weak pilot light flame at the burner 24.

From the lever 27, a chain or cord 28 extends vertically and passing over a movable pulley 29 and a fixed pulley 30, is attached to the free end of the crank or arm 18, and this connection is such that when the arm 18 moves through one-half of one revolution, that is to say, in moving to the point 19, it will raise the arm 27 of the valve 26 and cause an increase in the supply of gas to the pilot burner 24. This supply of gas when once thus increased would continue so long as the arm 18 is in engagement with the contact point 19 were not some independent means provided to diminish the flow. In other words, with the devices operative to the extent above described, the increased flow of illuminating gas would continue so long as the motor 1 runs and fuel is being consumed in the burner 6. Such an operation would, however, be useless because of the great waste of illuminating gas.

I, therefore, have provided a means for automatically reducing the flow of gas to the pilot light, back to the predetermined minimum after the heavy fuel is ignited and after the temperature of the furnace has been raised to a predetermined point.

At any suitable place within the furnace or boiler, as for instance, above the hot-water tubes or chambers 31, I provide a long metal bar 32 preferably of brass, and secure one end thereof to some rigid part of the heater structure. I thus preferably provide the end of the bar 32 with a hole through which passes a bolt 33, which in turn passes through clamps 34 and 35 resting respectively on opposite sides of the heater structure. When the nut 36 is secured to the bolt 33, the bar 32 will be rigidly attached at one end to the heater structure. The other end of the rod

32 may project outside of the boiler through any suitable opening in the boiler structure, as for instance, through a notch in the damper 37 in the smoke stack or passage 38. This rod 32 may however be located in any suitable place in the boiler, so long as it is attached at one end rigidly to the boiler structure, and its other end is free to actuate a mechanism, outside of the boiler, and the rod is where it may be heated and consequently caused to expand by the heat generated by the combustion of the fuel in the pot or burner 6.

I preferably attach to the outer projecting end of the bar 32 a pulley 39 around which passes a cord, chain or other flexible connection 40, one end of which is rigidly attached to some immovable object, as for instance, to a hook 41 secured to the wall of the building and the other end of which is provided with the movable pulley 29, the cord or chain 40 passing over suitably fixed or stationary sheave-pulleys 42, 43 in its passage to the pulley 29.

Now, continuing the description of the device from the point where the arm 18 is assumed to have moved into engagement with the contact point 19, atomized fuel is being supplied and burned within the burner 6, and the pilot light is being supplied with excess illuminating gas because the arm 27 is elevated, after the fuel from the nozzle 5 has been ignited. The heat evolved from the burning liquid fuel now immediately begins to raise the temperature of the boiler or heater. The flames will fill the fire-box or space above the burner, and will pass through the various passages of the boiler until they finally emerge in the passage 38 to the stack. In so doing they will sweep around and over the metal bar 32 and heat it. As the temperature of this bar 32 rises its length will increase. It will expand under the influence of the heat communicated thereto by the burning fuel in the pot 6. As this bar expands, the free end thereof, carrying the pulley 39, will move outwardly away from the furnace or boiler, and this motion will be multiplied at the free end of the cord or chain where the pulley 29 is attached by reason of the passage of the flexible connection 40 over the pulley or sheave 39 at the end thereof. As, therefore, the bar 32 expands, the pulley 29 on the free end of the cord 40 will move outwardly from the pulley 43 and downwardly, thus bringing the point at which the cord 28 passes over the pulley 29 nearer the pulley 30. As a result of this, the arm 27 will move downwardly under the influence of the weight 44 attached to the free end of the arm 27 to take up any slack that would otherwise be produced in the cord or chain 28.

The parts are so proportioned, arranged and located that when the heat of the burning atomized fuel is sufficient to expand the bar 32 a predetermined amount (e. g. one-half of

an inch to one inch), the lever 27 will move to the position wherein only the predetermined minimum amount of illuminating gas, merely sufficient to maintain the pilot light burning, will be supplied to the burner.

If, then, under these conditions, the bar 32 being hot and expanded, the temperature of the room or house, in which is the thermostat, reaches that predetermined high point which actuates the thermostat to stop the consumption of fuel by cutting off the current supplied to the motor 1. As soon as the arm 18 of the mechanism 14 starts to revolve through the second half of its complete revolution, it moves away from the contact 19 and breaks the circuit to the motor. The arm 18 will however continue its movement until it reaches the point shown in the drawing, at which point it will stop. As the arm 18 rises, the connection 28 will merely slacken, because the lever 27 had already dropped to the position shown in the drawing, by reason of the expansion of the bar 32. As the boiler or heater now cools, the bar 32 will contract and gradually draw the pulley 39 toward the boiler and this contraction will continue to take up the slack of the cord 28. In this position, the device is ready to operate again when the current is next supplied to the motor to start the projection of the heavy atomized fuel into the burner 6.

It is to be understood that the above description of my device is by way of illustration only. The bar 32 may be arranged in any suitable place within the heater. The movement of its free end due to the expansion and contraction thereof may be multiplied in any suitable way other than by a multiplying pulley 39, as for instance by any suitable arrangement of levers, and the arm 27 of the valve 26 may be held in its normal position to supply the minimum amount of gas to the pilot light by a spring instead of by a weight 44. The automatic device which has been described as the operating mechanism 14 may be actuated by a spring, or by a weight, or by an electric motor, so long as the arm 18 is given a movement in one direction in starting the operation of the burner and a movement in the reverse direction in stopping the current supply of atomized fuel to the burner. It will therefore be plain that I do not wish to be construed as limiting myself to the exact details of construction shown in the drawing forming a part of this specification.

The operating mechanism or controller 14 may be of any well-known and suitable construction. There are a number of them on the market which are actuated by a thermostat to start the motor of an oil burner or other mechanism and in which a crank or other suitable

external member moves in one direction to start the motor and in the other direction to stop it. The drawing forming a part of this specification is therefore diagrammatic in this respect and no attempt has been made to show or describe the mechanism within the casing thereof.

In the embodiment of my invention above described, I have attached the outside member 18 of the controller to the pilot light valve by a suitable connection 28, and the expandible bar 32, which may be considered as a second thermostat or thermostatic element, located in any suitable place within the heater structure where it is directly subjected to the heat produced by the combustion of the projected fuel, is operatively attached to the connection 28 and through it to the valve 26 to close the valve and reduce the enlarged pilot light flame to normal upon the expansion of said bar 32.

The pilot light may be located in any suitable place and in any suitable manner with respect to the pot or burner 6, provided, of course, that when the flame thereof is enlarged, it extends or projects into the spray of the fuel delivered to the burner from the fuel projector. The details of these constructions however may be considerably varied without departing from the spirit and scope of my invention.

Having thus described my invention, what I claim and desire to protect by Letters Patent of the United States, is:

In a heater the combination of a pot or burner, means to project atomized fuel into said burner comprising an atomizer and a motor to drive the same, a thermostat, a controller actuated by said thermostat to stop and start said motor, a pilot gas light, means to supply gas to said pilot light comprising a pipe and valve therein normally set to cause a small flame at said pilot light, a connection between said controller and said valve whereby when said controller is actuated to start said motor, said controller also opens said valve through said connection to enlarge the flame of said pilot light prior to the projection of fuel into the said pot and to maintain said enlarged flame until said fuel ignites, and a thermostatic element in said heater operative when expanded by the heat produced by the combustion of said atomized fuel to in effect substantially lengthen said connection and permit said valve to close and reduce said flame to a normal pilot light flame.

In witness whereof, I have hereunto set my hand this sixteenth day of January, 1923.

STEPHEN L. MERSHON.
